United States Patent Office

Des. 230,648
Patented Mar. 5, 1974

230,648

NEWSPAPER BOX

Murray M. Fibus, Youngstown, Ohio, assignor to Steel
City Corporation, Youngstown, Ohio

Filed May 25, 1972, Ser. No. 257,070

Term of patent 14 years

Int. Cl. D31—00

U.S. Cl. D74—9 R

FIG. 1

FIG. 2

FIG. 3

FIG. 4

FIG. 1 is a perspective view of a newspaper box showing my new design;

FIG. 2 is a rear perspective view thereof;

FIG. 3 is a perspective view with the lid of the box partially opened; and

FIG. 4 is a vertical section on line 4—4 of FIG. 1.

The end not seen is a mirror image of the end illustrated. The bottom is substantially plain.

I claim:

The ornamental design for a newspaper box, as shown and described.
